Primary Examiner — Dana K Weiland*Assistant Examiner* — Messina L Smith(74) *Attorney, Agent, or Firm* — Gregory L. Mayback; Dickinson Wright PLLC(57) **CLAIM**

The ornamental design for cookware, as shown and described.

DESCRIPTION

FIG. 1 is a side perspective view of cookware showing my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is top plan view thereof; and,

FIG. 7 is a bottom plan view thereof.

The broken lines shown in the figures depict portions of the cookware that form no part of the claimed design.
